CLAIM

The ornamental design for a baby bottle holder, as shown and described.

DESCRIPTION

FIG. 1 is a top plan view of a baby bottle holder, illustrating my new design, the bottom view comprising a mirror image thereof;

FIG. 2 is a left side elevational view thereof, the opposite side comprising a mirror image;

FIG. 3 is a front elevational view thereof;

FIG. 4 is a rear elevational view thereof; and,

FIG. 5 is a perspective view thereof illustrating the handle in a moved position.

FIG. 1FIG. 2*FIG. 3*FIG. 4*FIG. 5
